HOLDER FOR PUMICE STONE OR THE LIKE FOR CLEANING COOKING APPLIANCES

Charles E. Emmerson, 6331 Hollywood Blvd.,
Los Angeles, Calif.

Filed Apr. 14, 1960, Ser. No. 60,181

Term of patent 14 years

(Cl. D37—1)

FIG. 1 is a front perspective view taken from the top and right end of a holder for pumice stone or the like for cleaning cooking appliances;

FIG. 2 is a top plan view;

FIG. 3 is a front elevational view;

FIG. 4 is a rear elevational view;

FIG. 5 is a left end elevational view; and

FIG. 6 is a bottom plan view thereof.

I claim:

The ornamental design for a holder for pumice stone or the like for cleaning cooking appliances, as shown.
